TRANSMITTER CONTROL MECHANISM

Louis C. Anderson, Jr., Arlington Heights, and Arthur A. Hagstrom, Hoffman Estates, Roselle, Ill., assignors to Teletype Corporation, Skokie, Ill., a corporation of Delaware

Filed Oct. 17, 1962, Ser. No. 231,204

9 Claims. (Cl. 178—17)

This invention relates to a printing telegraph transmitter control mechanism including a manually operable control lever, and more particularly to a control mechanism capable of starting and stopping a telegraph transmitter and disabling its tape feeding mechanism.

Heretofore, complicated lever systems operable by one or more control levers were necessary in order to control these multiple function of a transmitter. The present control mechanism is an extremely simple control mechanism for a transmitter. Preferably, the transmitter is of the type disclosed in the copending application of L. C. Anderson, Jr., A. A. Hagstrom and R. A. Thienemann, Serial No. 231,199 filed October 17, 1962.

Accordingly, an object of the invention is to provide a control mechanism for a telegraph transmitter that performs multifarious functions with fewer and less expensive elements.

Another object of the invention is to provide a control lever that not only controls the starting and stopping of the transmitter but additionally is capable of disabling the tape feed mechanism to permit free wheeling of the tape feed wheel and to withdraw the tape-out sensing pin to further expedite movement of the tape through the transmitter during a free wheeling operation.

A feature of the invention is the provision of a spring urged detent that not only serves to detent the control lever in a given position but also serves to retain the control lever within the transmitter.

According to the preferred embodiment of the invention, a one-piece, molded plastic, control lever has its pivot shaft pivotally supported in retaining slots in a contact block and is detented in either an "on" or "off" position by a detent lever that also urges the control lever into the retaining slots in the contact block. An offset portion on the pivot shaft of the control lever is movable to control on/off contacts to either start or stop the transmitter. A depending portion offset from the control lever serves to disable the tape feeding and detenting mechanism and due to the contour of the depending extension also serves to lock these mechanisms in a disabled condition. An upwardly extending portion of the control lever is operable to engage a hook on the trailing end of a tape-out sensing pin and depress the tape-out sensing pin to permit the unobstructed movement of the tape through the transmitter when the control lever is in the free wheeling position.

Other features and advantages of the invention will become apparent from the following detailed description when considered in conjunction with the accompanying drawings wherein:

FIG. 1 is a plan view illustrating a transmitter control mechanism according to the preferred embodiment of the invention;

FIG. 2 is a sectional view taken along the line 2—2 in FIG. 1 in the direction of the arrows showing a tape-out sensing pin in its outward position;

FIG. 3 is a sectional view taken along the line 3—3 in FIG. 1 in the direction of the arrows showing the manually operable control lever and tape feeding mechanism, and

FIG. 4 is a view showing the manually operable control lever in its free wheeling position wherein the tape feeding mechanism is disabled.

The control mechanism hereinafter described is of a type that is disclosed in the copending application of L. C. Anderson, Jr., A. A. Hagstrom and R. A. Thienemann, Serial No. 231,199 filed October 17, 1962, which application is hereby incorporated by reference and to which reference may be had for a more complete disclosure of the transmitter in which the control mechanism is utilized. While the control mechanism, hereinafter described, is utilized in the above-identified transmitter, it will be apparent that the control mechanism is not limited to use only in this transmitter but is capable of use in other types of transmitters.

The control mechanism consists essentially of a molded one-piece plastic shaft 11 having a manually operable handle 12 (FIG. 3) integrally formed thereon and extending obliquely upward and a plurality of other integrally formed actuating arms or appendages thereon which will be described in detail hereinafter.

The shaft 11 terminates in extremities 13 of reduced diameter (FIG. 1) one of which is inserted in an aperture 14 therefor in a side wall 15 of a contact block 16 and the opposite of which is carried within a slot 17 formed in an opposite side wall 18 of the contact block 16. The shaft 11 is easily assembled within the contact block 16 merely by inserting the reduced extremity 13 within the aperture 14 and the sliding of the opposite extremity 13 downwardly in the slot 17. The shaft 11 is retained in this position by a detent lever 20 pivotally mounted on an upstanding tab 21 (FIG. 3) formed on the contact block 16. The detent lever 20 has detent notches 25 for detenting engagement with a projection 24 formed integrally on the shaft 11 and a contractile spring 22 connected between the detent lever 20 and a projection 23 on contact block 16 urges the detent notches 25 into engagement with the projection 24. As should be apparent the detent lever 20 thus serves to hold the shaft 11 in either the "run" or "stop" positions, to which it has been rotated, until an operator manipulates the handle 12 again.

When the manually operable handle 12 is in the "run" position, an energizing circuit is completed to start the transmitter operating and when the manually operable handle 12 is either in the "stop" or "free wheeling" positions, the energizing circuit for the transmitter is broken. The contact block 16 supports three upper wire contact springs 30 (FIG. 2) which are pivoted at one end on an upper rounded surface 31 of a contact connector 32 and which are biased downwardly by springs 33 interconnected between each of the wire contact springs 30 and individual tangs 34 formed integrally on the contact block 16. With this type of construction the contact springs are continuously urged to rotate in the counterclockwise direction, as seen in FIG. 2, and have their free ends urged downwardly into contact with the upper surface of a contact connector 35 carried within a hollow end wall 36 of the contact block 16. Each of the contact connectors 32 and 35 is in the energizing circuit of the transmitter and movement of a wire contact spring 30 into engagement with its associated contact connector 35 bridges and completes an energizing circuit for the transmitter that was formerly open between the wire contact spring 30 and its associated contact connector 35.

In FIG. 2 a lower wire contact spring 38 is shown urged into engagement with a common contact bar 39 under the urging of its associated spring 40. A plurality of wire contact springs 38 are provided and are adapted to have their other ends movable by sensing pins (not shown) thereby making and breaking contact with the common contact bar 39 as the code combinations are being sensed in a perforated record medium.

When the manually operable handle 12 is in its "stop" position, a laterally offset cam surface 42 integrally

formed on the shaft 11 is in a rotative position such that cam surface 42 has lifted the inner two of the wire contact springs 30, beneath which cam surface 42 is situated, into an upward position out of engagement with their associated contact connectors 35. Of course, when the manually operable handle 12 is rotated farther in the clockwise direction, to the "free wheeling" position illustrated in FIG. 4 the camming surface 42 has been rotated still higher and consequently lifts these two wire contact springs 30 farther away from their associated contact connectors 35.

When the handle 12 is rotated to the free wheeling position shown in FIG. 4, the shaft 11 rotates in a clockwise direction and a depending arm 45 integrally formed with the shaft 11 rotates therewith to bring its cam shaped extremity 46 into engagement with an inclined surface 47 on a blocking pawl 48 pivotally mounted on a pivot pin 49. During the movement of the handle 12 between the stop and free wheeling positions shown in FIGS. 3 and 4, the cam shaped extremity 46 engages the inclined surface 47 and causes the blocking pawl 48 to rock in a clockwise direction until the cam shaped extremity 46 is disposed within a locking indentation 50 formed immediately above the inclined surface 47 on the blocking pawl 48. As shown in FIG. 4, the locking indentation 50 serves to lock the shaft 11 in its "free wheeling" position against the return bias exerted thereon by the detent lever 20 and its spring 22.

Simultaneously with the rotation of the blocking pawl 48 in the clockwise direction against the urging of spring 51, a fork 52 on the blocking pawl 48 cams a pin 53 carried on feed pawl 54 in a clockwise direction about the pivot pin 55 against the urging of a feed pawl spring 56. During the latter portion of its clockwise movement the pin 53 engages an extension on 57 on detent lever 58 and causes the detent lever 58 to pivot clockwise about its pivot shaft 59 against the urging of its associated contact spring 60.

When the handle 12 is in the "free wheeling" position as shown in FIG. 4, the blocking pawl 48 has moved its blocking face 64 out of the path of rotation of the teeth on the ratchet wheel 65; has moved tooth 66 of the feed pawl 54 out of engagement with the ratchet teeth on ratchet wheel 65; and has moved rounded camming surface 67 on the detent pawl 58 out of engagement with the teeth on the ratchet wheel 65. With the pawls in the position shown in FIG. 4, the ratchet wheel 65 is now free to move in either the clockwise or counterclockwise direction upon the pulling or moving of a tape through the transmitter. The tape has feed hole perforations therein for meshing with feed pins 73 on a feed wheel 70. The feed wheel 70 is rotatable on a shaft 71 that carries ratchet wheel 65 and feed wheel 70 is interconnected with the ratchet wheel 65 by a sleeve 72 encircling the shaft 71.

To permit the rapid movement of tape through the transmitter in an unobstructed manner, it is desirable to withdraw a tape-out sensing pin 75 so that its sensing finger extremity 76 is beneath the outer surface of a curved tape guiding surface 77 on the transmitter and no longer biased into engagement with the tape. The tape-out sensing pin 75 is of a rather complex shape as shown in FIG. 2 and has a slot 78 formed therein to partially enclose a fixed pin 79. When there is no tape in the transmitter to depress the sensing finger extremity 76 below the guiding surface 77, a spring 80 attached to tape-out sensing pin 75 urges the tape sensing pin 75 upwardly and leftwardly to the position shown in FIG. 2 where the bottom of the slot 78 is in contact with the pin 79.

When the tape is present within the machine, the sensing finger extremity 76 is continuously urged by the attached spring 80 to engage the underside of the tape and to bear thereagainst as the tape is being fed forward. However, it is desirable when undergoing a "free wheeling" operation to remove this drag on the tape by moving

the sensing pin 75 downwardly and holding it downwardly so that the sensing finger extremity 76 no longer bears upward against the underside of the tape in contact with guiding surface 77. To this end, the control shaft 5 11 is provided with an integrally formed hook 81 that is positioned for hooking engagement with a downwardly bent hooked extremity 84 formed on the tape-out sensing pin 75. As the shaft 11 rotates and moves the hook 81 into engagement with the hooked extremity 84 of the tape sensing pin 75, the tape sensing pin 75 will move downwardly against the urging of the spring 80 in a direction controlled by the moving of the slot 78 along the fixed pin 79. The sensing pin 75 is oriented and guided to move downwardly and guided against movement in a lateral direction by a depending surface 85 formed thereon positioned between adjacent and rising guiding projections 86 formed in the contact block 16.

It should be noted that the sensing pin 75 has a laterally turned arm 87 which extends beneath all three of the wire contact springs 30 and which brings its insulated sleeve 88 thereon into engagement with the wire contact springs 30 to lift the springs 30 out of engagement with their contact connectors 35 when no tape is in the transmitter. Thus, the energizing circuit for the transmitter is opened when the sensing pin 75 moves upwardly and detects the absence of a tape within the transmitter.

From the foregoing it should be apparent that by the provision of a single, inexpensive, cast, plastic, control lever, a means is provided for enabling and disabling the 20 operation of the transmitter and for disabling both the transmitter and feed mechanism upon the movement of the lever to its respective "run," "stop" or "free wheeling" positions.

Although only one embodiment of the invention is 35 shown in the drawings and described in the foregoing specification, it will be understood that invention is not limited to the specific embodiment described but is capable of modification and rearrangement and substitution of parts and elements without departing from the spirit of the 40 invention.

What is claimed is:

1. In a tape sensing transmitter having contacts for controlling the operation thereof, a tape feed mechanism for feeding a perforated tape through the transmitter and a tape-out sensing pin for detecting the presence or absence of a tape within the transmitter, the improvement comprising a control means having:

- (a) a rotatable shaft mounted in said transmitter,
- (b) a manually operable handle means attached to said shaft for rotating said shaft to various positions,
- (c) a first means operable by said shaft for controlling the condition of said contacts to start and stop operation of said transmitter,
- (d) a second means controlled by said shaft for disengaging said tape feed mechanism and for maintaining said tape feed mechanism disabled, and
- (e) a third means operable by said rotatable shaft for depressing said tape-out sensing pin thereby permitting the tape to be moved freely through the transmitter.

2. In a tape sensing transmitter having contacts for controlling the electrical energization and de-energization thereof, a tape feeding mechanism operable to feed a tape therethrough, and a tape-out sensing pin for detecting the presence or absence of a tape therein, the improvement comprising a control means having:

- (a) a rotatable means mounted in said transmitter,
- (b) an integrally formed and manually operable extension on said rotatable means for rotating said rotatable means between various positions,
- (c) a first integrally formed means on said rotatable means for operating said contacts upon rotation of said rotatable means to predetermined positions,
- (d) a second integrally formed means on said rotatable means for disabling said tape feeding mechanism

- and for holding said tape feeding mechanism in its disabled condition while said rotatable means is in a predetermined position, and
- (e) a third, integrally formed means on said rotatable means for depressing said tape-out sensing pin to prevent it from hindering movement of the tape through the tape transmitter.
3. In the transmitter of claim 2, a frame having at least one slot therein for supporting said rotatable means for rotary movement, and a detent means urged into engagement with said rotatable means to detent said rotatable means in at least one of its predetermined positions and to retain said rotatable means in the slot in said frame.
4. In the transmitter of claim 2, wherein said rotatable means is a shaft of one-piece, plastic construction.
5. In a tape sensing transmitter having contacts for controlling the operation thereof, a tape feed mechanism for feeding a perforated tape through the transmitter and a tape-out sensing pin for detecting the presence or absence of a tape within the transmitter, the improvement comprising a single oscillatable control member having integrally formed thereon:
- (a) a hook for engaging a portion of the tape-out sensing pin to retract said pin from its detecting position,
  - (b) a plurality of cam surfaces for opening various of said contacts in various oscillatory positions of said member, and
  - (c) an arm having a camming extremity for disabling the tape feed mechanism by camming a blocking pawl to a predetermined position to disengage said pawl, a drive pawl and a detent from a feed ratchet.
6. In a transmitter having a tape feed mechanism with a ratchet wheel operable by a feed pawl to rotate a tape feed wheel to feed the tape forward through the transmitter, the improvement comprising:
- (a) a detent lever means urged into engagement with said ratchet wheel to hold said ratchet wheel against movement until said feed pawl rotates said ratchet wheel,
  - (b) a blocking means movable into position to engage said ratchet with said feed pawl wheel and to limit overtravel of the ratchet wheel and the tape feed wheel due to their inertia, and
  - (c) a manually operable control means movable between various positions, and
  - (d) means operable by said manually operable control means to move feed pawl, said detent lever, and said blocking means to an inoperative position with respect to said ratchet wheel.
7. In a tape sensing transmitter having a tape feed mechanism with a ratchet wheel operable by a feed pawl to rotate a feed wheel to feed a perforated tape therethrough, the improvement comprising:
- (a) a detent lever urged into engagement with said ratchet wheel to hold said ratchet wheel against movement except by said feed pawl,
  - (b) said feed pawl having an extension thereon operable to move said detent lever to a noneffective position,
  - (c) a blocking pawl having a slot therein for receiving said extension on the feed pawl whereby movement of said blocking pawl causes a movement of said feed pawl and whereby movement of said feed pawl causes movement of said blocking pawl,

- (d) a camming surface on said blocking pawl,
  - (e) a detent surface on said blocking pawl, and
  - (f) a control lever having an extension for camming said blocking pawl to an inoperative position and thereby carrying said feed pawl to a position where it is effective through the extension on the feed pawl to move said detent lever to a noneffective position, said extension on said control lever also movable into the detenting surface on the blocking pawl to hold said blocking lever and detent lever in their inoperative position.
8. In a tape sensing transmitter having a tape feed mechanism including a ratchet wheel operable by a feed pawl to rotate a feed wheel to feed a perforated tape therethrough, the improvement comprising:
- (a) a detent lever urged into engagement with said ratchet wheel to hold said ratchet wheel against movement except by said feed pawl,
  - (b) a blocking means movable into engagement with said ratchet wheel to limit overtravel of said ratchet wheel and tape wheel due to their inertia,
  - (c) means on said feed pawl operable to move said blocking pawl into engagement with said ratchet wheel when said feed pawl moves in one direction and operable when said feed pawl moves in the opposite direction to move said feed pawl to move said blocking pawl from engaging said feed wheel, said means on said feed pawl also operable to move said detent lever from engagement with said ratchet wheel when said feed pawl is moving to a predetermined, free wheeling position, and
  - (d) a manually operable control means for moving said feed pawl and said blocking means to an inoperative, free wheeling position and thereby through said means on said feed pawl causing said detent lever to be moved to a free wheeling position.
9. In a tape sensing transmitter having a tape feed mechanism including a ratchet wheel operable by a feed pawl lever means to rotate a feed wheel to feed a perforated tape therethrough, the improvement comprising:
- (a) a detent lever means urged into engagement with said ratchet wheel to hold said ratchet wheel against movement except by said feed pawl lever means,
  - (b) a blocking lever means movable into engagement with the ratchet wheel during the terminal portion of a tape feeding cycle by said feed pawl lever means to limit the amount of rotation of said ratchet wheel,
  - (c) cooperable means on said feed pawl and blocking lever means to cause said feed pawl and blocking lever means to move simultaneously toward said ratchet wheel and away from said ratchet wheel,
  - (d) means on said detent lever means operable during movement of said feed pawl and blocking lever means to an inoperative position to cause said detent lever means to move to an inoperative position, and
  - (e) a manually operable control means operable to rotate one of said lever means to an inoperative, free wheeling, position and thereby through said cooperable means to move said feed pawl and blocking lever means to ensure their movement to an inoperative, free wheeling position and also to ensure movement of said detent lever means to an inoperative position.
